(57) **CLAIM**

The ornamental design for a cake cone, as shown.

DESCRIPTION

FIG. 1, is a top perspective view of a cake cone, showing my new design.

FIG. 2, is a top plan view of the cake cone of FIG. 1.

FIG. 3, is a side elevational view of the cake cone of FIG. 1.

FIG. 4, is a bottom plan view of the cake cone of FIG. 1.
FIG. 5, is a top perspective view of another embodiment of a cake cone, showing my new design.

FIG. 6, is a top plan view of the cake cone of FIG. 5.

FIG. 7, is a side elevational view of the cake cone of FIG. 5; and,

FIG. 8, is a bottom plan view of the cake cone of FIG. 5.
